UNITED STATES PATENT OFFICE.

PAUL DUMONT, OF NEW YORK, N. Y.

DESIGN FOR A STATUE.

SPECIFICATION forming part of Design No. 17,106, dated February 8, 1887.

Application filed November 16, 1886. Serial No. 219,097. Term of patent 7 years.

To all whom it may concern:

Be it known that I, PAUL DUMONT, a resident of New York city, in the county and State of New York, have invented and produced a new and original Design for a Statue, of which the following is a full, clear, and exact description, reference being made to the accompanying drawing, which represents a perspective view of my new design for a statue.

10 This invention relates to a new configuration of a statue.

The design consists in the representation of a female figure standing on the representation of the terrestrial globe, said globe bearing a ribbon or scroll for an inscription.

15 In the accompanying drawing, the letter A represents a female figure with one arm outstretched and holding a torch, which stands upon a representation of the terrestrial globe 20 B, the said globe constituting the base of the

statue, and having a convex lower side, as shown. The globe B has the ribbon or scroll C on its surface.

Having now described my design, what I claim is—

25 1. In a design for a statue, the representation of a female figure with one arm outstretched and holding a torch, standing on a representation of the complete terrestrial globe, the globe forming the base of the statue, substantially as shown.

30 2. In a design for a statue, the representation of a female figure standing on a representation of the terrestrial globe, the latter having on its surface a scroll or ribbon, substantially as shown.

PAUL DUMONT.
